AUGUST SUNDH, OF YONKERS, NEW YORK, ASSIGNOR TO OTIS ELEVATOR COMPANY,
OF JERSEY CITY, NEW JERSEY, A CORPORATION OF NEW JERSEY.

OVERLOAD MOTOR-CONTROLLING APPARATUS.

1,111,240.

Specification of Letters Patent. Patented Sept. 22, 1914.

Application filed August 16, 1907. Serial No. 388,812.

To all whom it may concern:

Be it known that I, AUGUST SUNDH, a citizen of the United States, residing at Yonkers, in the county of Westchester and State of New York, have invented a new and useful Improvement in Overload Motor-Controlling Apparatus, of which the following is a specification:

My invention relates to a system of electric motor control and has for its object the provision of automatic means for starting and accelerating an electric motor.

Another object is the provision of automatic means for operating a circuit breaker in the event of long continued flow of excessive current to the motor.

Further objects will appear hereinafter, the novel combinations of elements being pointed out in the appended claims.

20 The accompanying sheet of drawing illustrates diagrammatically a simple wiring plan whereby I accomplish my various objects.

Generally speaking my method of automatically starting and accelerating an electric motor consists in a series of electrically operated relays which control a starting resistance in series with the motor armature. These relays are operated by the counter-30 electro-motive force of the motor which is substantially proportional to its speed. A second series of electrically operated relays controlled by the first named relays control a portion of the motor starting resistance and depend for their operation upon a time element. Another electrically operated switch controls a circuit breaker under certain conditions of overload or excessive current flow.

40 While my system of motor control is adapted to either a direct, alternating, or pulsating current electric motor, in order to make the wiring diagram as simple as possible so that the same may readily be understood, I have chosen for purpose of illustration, a simple shunt wound direct current motor in which A designates the motor armature, and B the shunt field winding.

C designates a combined main line switch 50 and circuit breaker having a switch arm 31 upon which, but insulated from it, are mounted contacts 33' and 34'.

32 is a slot in the switch arm 31 and 37 is a compression spring whose tension may be varied by means of a set screw 38.

A trip lever 26 is pivoted at 27 and is normally held in a horizontal position against a stop 28 by means of a spring 29, which may be adjusted by a set screw 30. One end of this trip lever 26 is in engagement with the switch arm 31 and holds the latter in closed position against the action of the spring 37. When in such closed position the contacts 33' and 34' are held in electrical engagement with two fixed contacts 33 and 34 respectively. The other end of this trip lever 26 is in vertical alinement with the core 47 of the relay I.

36 designates an insulated handle connected to the switch arm 31 and is for the purpose of manually closing the switch C after the latter has been opened in a manner hereinafter pointed out.

D is a manually operated controlling switch which comprises a switch lever pivoted at 9 and carrying an insulated sliding contact 10 which is adapted to move over fixed contacts 11 and 12.

E designates a main line relay comprising a magnet winding or solenoid 76 and core 48 which carries on an extension of its upper end a contact plate 49 which is adapted when raised by the solenoid 76 to bridge, or electrically connect together, two fixed contacts 13 directly above and in line with it.

The relays 1, 2, 3 and 4, control the starting resistance F which is shown divided into four sections 68, 69, 70 and 71. The relay 1 comprises a winding 77 and magnet core 50 having an extension piece at its upper end to which is attached a contact plate 51 adapted when raised to engage fixed contacts 14. The lower end of the core 50 carries a contact plate 52 which is insulated therefrom and which normally bridges or short circuits stationary contacts 53 and 54. A spring 5 partially counterbalances the core 50, and its connected contact plates and is capable of adjustment by means of the set screw 55. The relay 2 has a winding 78, core 59, contact plate 65, and spring 6 similar to those of relay 1 and controls the fixed contacts 15, but the lower contact plate and coöperating fixed contacts are omitted. The relay 3 controls the fixed contacts 16 and lower contacts 62 and 63 and is similar to relay 1, while the relay 4 is similar to relay 2 and controls the fixed contacts 17. The set screws 55, 56, 57 and 58 by which the respective springs 5, 6, 7 and 8 may be ad-

justed are all threaded into a common piece of insulating material 87. The relays G and H are similar and comprise magnet windings and cores 39 and 42 at the upper ends of which are rods carrying insulated contact plates 40 and 41 which are adapted when raised to bridge fixed contacts 18 and 19 respectively directly above. The lower end of each core is connected by a rod to the piston of a dash pot device 20 and 21 provided with ball check valves 23 and 24 respectively, which latter operate in a well-known manner allowing their respective dashpot pistons to move freely in a downward direction but retarding the same when moved upwardly. The dashpot rods carry insulated pieces 82 and 84 upon which are mounted contacts 43 and 44 adapted when raised to engage fixed contacts 45 and 46 respectively. The relay I is provided with a magnet winding or solenoid and core 47 whose upper end engages the trip lever 26 under certain conditions which will be pointed out later, and whose lower end is connected by a rod to the piston of a dashpot device 22, which is similar to the dashpots used with the relays G and H.

Under normal conditions the main line switch or circuit breaker C is closed as shown and the positive and negative current supply wires designated by + and — are connected through the contacts 33, 33' and 34, 34', respectively to the main feed wires 85 and 74 respectively. The circuit to the motor is as follows: from the positive main by wire 85 to the brush 73, motor armature A, brush 72, starting resistance F and by contacts 13 and contact plate 49 when the same are in closed relation, to the negative wire 74. The shunt field B has one terminal connected at 81 to the positive wire 85, the other terminal is connected by wires 82, 88, and 89 and contacts 13 when the latter are closed to the negative main 74. It will be noticed that both the armature and shunt field circuits are open circuited at the contacts 13 when the relay E is not energized to raise the contact plate 49 and bridge the contacts 13. The magnet windings 77, 78, 79, and 80 of the relays 1, 2, 3 and 4, respectively, are connected in series with each other and one outside terminal is connected by the wire 90 to the brush 72. The other outside terminal is connected to the other brush 73 by the wires 86 and 85. These windings are therefore in parallel relation to the motor armature A.

I will now describe the operation of my motor controlling system.

Assuming that the main line switch C is closed as shown, the manually operated switch D is moved to the right until the sliding contact 10 bridges the fixed contacts 11 and 12. This operation closes a circuit through the winding of relay E and

also a circuit through the relay G. These circuits may be traced as follows:—The circuit to the relay E is from the positive main feed wire 85, wire 86, winding 76, contacts 12, 10 and 11, to the negative feed wire 74. The circuit to the relay G is from the positive feed wire 85, winding of relay G, wire 91, contact 54, contact plate 52, contact 53 and to the negative feed wire 74 by way of the switch D. Now since the winding of relay E is in a closed circuit across the mains 85 and 74, it becomes energized to raise its core 48 and thereby bridge the contacts 13. As before pointed out, this closes the motor circuit through the starting resistance F and also closes a circuit through the shunt field B and the motor will start, its current being limited in amount by the starting resistance F. As the motor accelerates in speed it will generate a counter-electro-motive force which increases with the speed, and, since the relays 1, 2, 3, and 4 are connected in parallel to the motor armature they will become more and more energized as the counter-electro-motive force increases until finally the relay 1 will raise its core and connected parts thereby short-circuiting a portion 68 of the starting resistance and at the same time open circuiting the magnet winding of the relay G at the contact 54 of relay 1. Since a portion of the starting resistance designated by 68 has been short-circuited the motor receives additional current from the main line and its speed increases accompanied by a further increase of counter-electro-motive-force. More current will therefore flow in the windings of the relays 1, 2, 3 and 4 and the relay 2 becomes sufficiently energized to raise its core and connected contact plate 65. As this contact plate is raised it will bridge the contacts 15 and another portion 69 of the starting resistance is short-circuited followed by a further increase of motor speed. In a similar manner the relays 3 and 4 are energized in successive order to short-circuit the remaining starting resistance and the motor rapidly assumes full speed. current from the main line flowing directly to the motor armature with no starting resistance in circuit. The relay G will not operate when the motor is started with normal load for the reason that the dashpot 20 which is connected to the core of the relay, retards its upward movement until after the first accelerating relay 1 has operated and the circuit to the relay G is then opened at the contact 54. The relays H and I cannot operate since their windings are open-circuited at the contacts 45 and 46 respectively. The relay I is also open-circuited at the contact 63 as soon as the accelerating relay 3 has operated.

The foregoing description shows the operation of the system under normal conditions

of load. Now in many places where a motor is used, as for example, to operate an elevator, it frequently happens that the motor before starting is overloaded and the starting resistance does not allow the motor armature to receive sufficient current to start the excessive load, and since the motor does not under these circumstances generate any counter-electro-motive-force, the accelerating relays 1, 2, 3 and 4 cannot operate to close their contacts and short-circuit the starting resistance and the result will be to merely heat the resistance. In order to prevent this needless waste of current and at the same time to make it possible for the motor to start the overload, I provide the relays G and H. The operation of the system in starting with an overload is, as follows:—Upon closing the hand switch D the relay E will be energized as before and complete the motor circuit also a circuit to the shunt field B and winding of relay G and the latter will be energized to slowly raise its core and connected contact devices retarded by the dashpot 20. As soon as the contact plate 40 bridges the contacts 18 the first section 68 of the starting resistance is short-circuited and the motor now receives additional current and is enabled to start its load. As the motor accelerates, the relays 1, 2, 3 and 4 operate successively as before, to short-circuit the entire starting resistance. As soon, however, as the relay 1 operates, the relay G is open-circuited at the contact 54 and drops back to its original position. Should the motor refuse to start when the first section 68 of the starting resistance is short-circuited, the relay H will receive current by way of the contacts 43 and 45 which are closed by the relay G. The winding of relay H is now connected in parallel to the winding of relay G and it will slowly operate to close the contacts 19 and the contacts 44 and 46. The contacts 19 short-circuit the section 69 of the starting resistance, and the contacts 44 and 46 close a circuit to the winding of the relay I connecting the same in parallel to the relays G and H through the contacts 63 and 62, of the relay 3. The relay I is therefore energized and raises its core slowly under the retarding action of the dashpot 22. Should the motor be unable to start after the sections 68 and 69 of the starting resistance have been short-circuited, the relay I will finally engage the trip lever 26 of the main line switch C and the lever will swing about the pivot 27 until the right-hand end registers with the slot 32. The spring 37 is now enabled to open the switch C thereby separating the contacts 33, 33' and 34, 34' respectively, and all current supply is at once cut off from the motor and other circuits and all the parts return to normal positions. Should the motor start after the relays G and H have operated to short circuit the sections 68 and 69 of the starting resistance, the accelerating relays will operate in their successive order as the motor accelerates and the windings of the relays G and H will thereupon become open-circuited at the contacts 54 and 53 of relay 1 and will drop their cores. Since the circuit of relay H is closed by the relay G and the circuit of relay I is closed by the relay H, it follows that each of these relays will operate in a predetermined order since the circuit of one relay depends upon the previous operation of its companion relay. In the event of the relay 1 refusing to operate and the relays G and H close their contacts, thus energizing the relay I, the accelerating relay 3 will operate to open the circuit to the relay I at the contacts 63 and 62, and the main line switch C, consequently will not be tripped to open the motor circuit.

From the foregoing description it will readily be seen that the motor is effectually safeguarded from long continued flow of excessive starting current, for while it may be necessary in order to start an overload to give the motor current greatly in excess of its normal starting current, it is neither safe nor desirable to allow this excessive current to flow for any great length of time. The relay I may be adjusted to trip the main line switch after a certain interval of time has elapsed, depending upon the adjustment of the dashpot 22 which may be provided with a valve or air cock to regulate the admission of air or other fluid under the dashpot piston in a well-known way.

The accelerating relays 1, 2, 3 and 4 are adjusted so that they will operate successively in a predetermined order. This may be done by varying the tension of the springs 5, 6, 7 and 8 respectively or by varying the distance which the cores of the relays have to travel in order to close their respective contacts.

While I have shown but four accelerating relays and a corresponding number of sections into which the starting resistance is divided, the number of relays and resistance sections may be more or less than four, depending to a large extent upon the duty and capacity of the motor. Where a compound motor is used I frequently arrange the accelerating relays to first short-circuit the starting resistance and then short-circuit the series field in one or more steps. Any desired number of relays such as G and H may be used as I do not desire to limit myself to any particular number, the principle of operation being the same regardless of the number of relays connected in circuit.

What I claim as new and desire to protect by Letters Patent of the United States is:—

1. The combination of a motor having a sectional starting resistance, a source of elec-

4. Electric current, means controlled by the counter-electro-motive force of the motor for successively cutting out the sections of resistance, and additional means for cutting out said resistance upon failure of said first-named means to operate. 70
5. The combination of an electric motor, having a starting resistance, a source of current supply for the motor, a circuit connected across the brushes of the motor, electro-magnetic means in said circuit for controlling the starting resistance, and additional means dependent upon the load to control the resistance. 75
10. 3. The combination of an electric motor having a starting resistance, means for automatically cutting out a portion of said resistance as the speed of the armature increases, and additional means for cutting out a portion of the starting resistance upon failure of the first means to operate. 80
15. 4. The combination of an electric motor, having a sectional starting resistance, automatic means for cutting out a portion of the resistance as the speed of the armature increases, and additional means for cutting out said portion of the resistance upon failure of the first means to operate. 85
20. 5. The combination of an electric motor having a sectional starting resistance, a plurality of electromagnets operative successively to cut out the sections of resistance as the armature speed increases, and means for cutting out said sections upon failure of the 90 electromagnets to operate. 95
25. 6. The combination of an electric motor having a sectional starting resistance, a plurality of electromagnets operative successively to short-circuit the sections of the starting resistance, and additional electromagnets operative to cut out the sections of starting resistance upon the failure of the first electromagnets to operate. 100
30. 7. The combination of an electric motor having a starting resistance, a plurality of electromagnets operative successively to cut out portions of said resistance, additional electromagnets operative successively to cut out portions of the starting resistance upon failure of the first named electromagnets to operate, and means for retarding the operation of said additional electromagnets. 105
35. 8. The combination of an electric motor, a sectional starting resistance therefor, a circuit connected across the motor armature, a plurality of electromagnets in said circuit operative successively as the current through said circuit increases, means operated by the electromagnets for successively cutting out the sections of the starting resistance, and retarded mechanism for cutting out a portion of said resistance upon failure of said electromagnets to operate within a predetermined time limit. 110
40. 9. The combination of an electric motor, a sectional starting resistance therefor, a circuit in parallel with the motor armature, a plurality of electromagnets in said circuit, operative successively as the current through said circuit increases, means operated by the electromagnets for successively cutting out portions of the starting resistance, and means operated thereby to cut out a portion of the starting resistance upon failure of the other electromagnets to operate. 115
45. 10. The combination of an electric motor, a starting resistance, a circuit in parallel with the motor armature, a plurality of electromagnets in said circuit, operative successively as the current through said circuit increases, means operated by the electromagnets for successively cutting out portions of the starting resistance, a retarded electromagnet, and means operated thereby to cut out a portion of the starting resistance upon failure of the other electromagnets to operate. 120
50. 11. The combination of an electric motor, a starting resistance, a circuit in parallel with the motor armature, a series of electromagnets in said circuit, operative successively as the current through said circuit increases, means operated by the electromagnets for successively cutting out portions of the starting resistance, a second series of electromagnets operative successively, means operated by the second series of electromagnets for cutting out portions of the starting resistance upon failure of the first series of magnets to operate, means for retarding the 125 operation of the second series of electromagnets. 130
55. 12. The combination of a motor, a starting resistance, an electromagnet, means operated thereby for cutting out a portion of the resistance, a second electromagnet, means operated thereby for cutting out a portion of the resistance upon failure of the first electromagnet to operate, means for opening the circuit through the second electromagnet when the first operates, and means for retarding the operation of the second electromagnet to give the first one time to operate. 135
60. 13. The combination of an electric motor, a starting resistance, a series of electromagnets arranged and adapted to be successively operated, means operated by the magnets for successively short-circuiting portions of the resistance, a second series of electromagnets, means for causing them to operate successively upon failure of the first electromagnets to operate, means operated by said second series of magnets for successively short-circuiting portions of the starting resistance, means operated by the first series of electromagnets to render the second series inoperative, and means for retarding the operation of the second series to give the first series time to operate. 140

14. The combination of an electric motor, starting resistance, an electric circuit in parallel with the armature of the motor, a plurality of electromagnets operative with current of different strength and having their windings in said circuit, said electromagnets being arranged to operate successively as the speed of the armature increases and thereby increases the counter-electromotive force, means operated by said electromagnets for successively short-circuiting portions of the starting resistance, and retarded means independent of the speed of the armature for short circuiting portions of the starting resistance when the electromagnets fail to operate.
15. The combination of a motor, automatic means for controlling the acceleration of the motor, a circuit breaker operative upon failure of said means to operate, and means controlled by the counter-electro-motive force of the motor for preventing the operation of the circuit breaker when said controlling means operates.
16. The combination of an electric motor, a source of current therefor, a starting resistance in the motor circuit, a device to automatically open the motor circuit upon failure of the motor to start when its circuit has been closed, and electro-responsive means controlling said resistance dependent upon the counter-electro-motive force developed by the motor for normally preventing the operation of said device.
17. The combination of a motor, a source of current, a starting resistance in the motor circuit, retarded means for automatically opening the motor circuit upon failure of the motor to start within a predetermined time after its circuit is closed, and electro-responsive means controlling said resistance dependent upon the operation and development of a certain speed of the motor for preventing the operation of said retarded means.
18. The combination of an electric motor, a starting resistance therefor, a source of current, means for opening the motor circuit upon failure of the motor to develop a given speed within a given time after the motor circuit has been closed and before said resistance has been cut out of the motor circuit, and an electro-responsive device for rendering said means inoperative when the motor develops said speed, said device being dependent for its operation upon the motor developing said speed.
19. The combination of a motor, a source of electric current for the motor, a starting resistance in the motor circuit, a circuit breaker, retarded means for operating the circuit breaker in a predetermined time after the motor circuit is closed and before the
- said resistance has been cut out of the motor circuit, and electro-responsive means controlled by the speed of the motor for rendering said retarded means inoperative.
20. The combination of a motor, a source of current supply, an automatic switch in the motor circuit, a starting resistance, automatic electromagnet relays for cutting out the resistance when the motor has started, retarded means for opening the automatic switch, and means operated by the magnets of said relays for rendering the said switch-opening means inoperative.
21. The combination of a motor, a source of current supply, a starting resistance, a circuit in parallel with the motor armature, an electromagnet having its winding in said circuit and operative when the motor has developed a predetermined counter-electro-motive force, means operated by said electromagnet to short-circuit the starting resistance, a circuit breaker in the motor circuit, a second electromagnet and means for causing it to operate when the circuit through the motor is closed, means operated thereby for short-circuiting the starting resistance, means also controlled by said second electromagnet for opening the circuit breaker, means for retarding the operation of the second electromagnet, and means operative upon the operation of the first-electromagnet to render the second electromagnet inoperative, and thus prevent the opening of the circuit-breaker.
22. The combination of an electric motor, a starting resistance, a circuit in parallel with the motor, a plurality of electromagnets in said circuit operative successively as the speed of the motor increases, means operated by the electromagnets for successively cutting out portions of the starting resistance, a second series of electromagnets, the first magnet of said series having its winding in a circuit which is closed when the circuit through the motor is closed, means operated by each of said second series of electromagnets for closing a circuit through the succeeding magnet of the series, to operate said magnets successively, means operated by each of said second series of electromagnets for short-circuiting a portion of the starting resistance, means operated by the first series of magnets for opening the circuit through the second series and rendering them inoperative, means for retarding the operation of the electromagnets in the second series, a circuit breaker in the motor circuit, means operated by the last of the second series of electromagnets for causing the circuit-breaker to operate, and means for retarding the operation of the circuit breaker.
23. The combination with an electric mo-

tor and accelerating apparatus therefor, of
means controlled by the counter-electromotive
force of the motor for operating said
accelerating apparatus, and additional
means for operating said apparatus upon the
failure of first named means to operate.

In testimony whereof, I have signed my

name to this specification in the presence of
two subscribing witnesses.
